UNITED STATES PATENT OFFICE.

HARRY LANDSIEDEL, OF CINCINNATI, OHIO, ASSIGNOR TO THE DALTON ADDING MACHINE COMPANY, OF CINCINNATI, OHIO, A CORPORATION OF OHIO.

NONPRINT MECHANISM FOR ADDING MACHINES.

Application filed October 4, 1922, Serial No. 592,197. Renewed September 18, 1926.

This invention relates to a mechanism for use primarily in connection with an adding or similar computing machine in which, in its normal operation, type bars or sectors are moved to the requisite positions to bring the intended numbers to the printing line, after which, upon reciprocation of the handle, hammers are released to drive the type against the inking ribbon backed by the platen to record the selected numerals on the paper.

An object of the present invention is to provide simple and positive means for the non-printing of figures which secures the results stated by preventing the release of the hammers. A similar result has heretofore been accomplished by locking the movement of the hammers after they have been released but before the type has been struck, which method, however, results in an idle and unnecessary firing of the hammers which is a less desirable method than the one herein described.

A further object is to provide means for latching down the non-print key, so that a single set of numeral figures may be non-printed and also to provide locking means whereby the operator may non-print any number of items without further attention to the key.

A further object is to provide means for blocking the movement of the platen carriage mechanism, so that the platen will not rotate when the non-print key is depressed to its operative position.

Means whereby the above results are attained comprise the essential features of the present invention which will now be described.

40 In the drawings:

Figure 1 is a side elevation of a Dalton adding machine, illustrating in part the arrangement of the various important units. For example, the adding and printing racks, movable stop carriage, the numeral key levers, the main shaft, the platen carriage, and the non-print mechanism;

Fig. 2 is a front view of the non-print key and hammer section;

50 Fig. 3 is a side view of the printing mechanism and the platen drive shaft blocking mechanism;

Fig. 4 is a side view of the non-print key

depressed when the operating lever is normal;

55 Fig. 5 is a similar view, showing the position that the parts assume when the operating lever is in its extreme forward position;

Fig. 6 is a view showing the non-print keys in normal or raised position with the train of connections for actuating the platen; and

60 Fig. 7 is a similar view showing the position assumed when the operating handle is pulled forward.

The machine, as a whole, is mounted upon a base 10 which supports side walls 11 connected by means of a top plate 12 upon which is mounted a hood 13 which houses a series of hammers 14 which co-act with a series of type carriers 15 carrying movable type 16, one hammer being provided for each set of nine type carriers, and adapted to strike the particular type of the series which is moved to the printing line. The type co-act with a platen 17 which is adapted to be rotated by suitable mechanism shown in Figs. 6 and 7 in a manner well known in the adding machine art.

65 Each type carrier 15 is mounted upon and forms part of a sector 18, which sectors are freely mounted upon a fixed shaft 19 and arranged with each sector is an adding rack 20. Each rack is provided with a heel 21 which is adapted to be stopped by any one of a series of movable stops 22 mounted in a transversely traveling carriage 23. The stops are adapted to be set up by the action of tappets 24 carried by key levers 25 terminating in keys 26.

70 The above mechanisms constitute some of the more important elements of a Dalton adding machine, but the specific construction and mode of operation of these parts is well understood by those skilled in the art, and further description thereof is deemed unnecessary.

75 Each hammer 14 of the bank of hammers is pivoted upon a cross bar 27, and each hammer is provided with a hooked tail piece 28 which co-acts with the aligned member of a series of latches 29, the number of latches being equal to the number of hammers. Each latch 29 is of the configuration best shown in Fig. 3, being provided with an inwardly extending tongue 30 which bears 80 against a stud 31 carried by the co-acting

type carrier. Each latch is further provided with a hooked heel 32 which is engaged by a spring 33, and all of the latches of the series bear against a cross bar 34 which constitutes a universal fulcrum for the series of latches.

Each latch tongue is provided at an intermediate point on its upper edge with a projecting finger 35, and all of the fingers occupy positions in proximate relation to a universal firing bar 36 which extends transversely of the machine in a plane slightly above the series of fingers when depressed as in Fig. 3. One end of the firing bar is carried by a firing bar bell crank 37, and its opposite end rides in a slot 38 in one of the side walls 11 of the machine. The bell crank 37 is pivoted upon a cross rod 39 and its lower arm 40 carries a roller 41 which rides upon a cam 42 secured to and movable with the full stroke sector 43, which is mounted upon the usual handle operated shaft 44. The cam 42 is provided near its end with a depression 45, and the upper arm of the bell crank is engaged by a spring 46, so that when the cam 42 is oscillated forwardly to its extreme limit by the movement of the handle, the roller 41 will ride down into the depression 45, thereby allowing the upper end of the bell crank to swing rearwardly and move the firing bar to the rear.

On the beginning of the forward stroke of the handle the sectors which have been released and are to move to printing position will rise in varying degrees as limited by the steps in the transversely movable carriage, and these movements of the respective sectors will, in each instance, lift the several studs 31 allowing the tongues of the corresponding number of hammer latches to rise. These lifting movements of the tongues will lift the respective fingers 35 into contact with the under side of the firing bar, and at the terminus of the forward stroke of the handle, the firing bar will move to the rear, as stated, thereby allowing the requisite number of projecting fingers 35 to spring upwardly into position to engage the forward edge of the firing bar when in its rearward position without, however, effecting a release of the hammer-tail pieces 28 at this stage of the operation.

However, upon the beginning of the return movement of the handle, the elevated portion of the cam 42 will sweep under the roller 41, thereby swinging the upper end of the bell crank 37 forwardly and with it the firing bar which will thus carry forward the engaged number of latches and effect a release of a like number of hammers which will be fired by the tension of springs 46, one spring being provided for each hammer.

The above mechanisms act in the manner stated during the normal operation of the machine, but in order to disable such mecha-

nisms and prevent printing, the following devices are provided:

At one end of the hood 13 is a non-print key 47 forwardly extending from a vertical shank portion 48 provided with upper and lower slots 49 and 50, the former of which receives a guide pin 51 outwardly projecting from a vertically disposed boss 53 secured to or formed upon the proximate end of the hood. The shank 48 extends through a slot 54 in the top plate 12, and said shank on its inner edge is provided with a shoulder 55 which, when the shank is depressed by the movement of the key, is adapted to hook under the inner end of the slot to hold the key in depressed condition. The key shank 48 is provided near its lower end with a heel 56 which normally occupies a position slightly to the rear of and above the plane of the firing bar 36, being normally held in this position by the tension of the spring 57. When the key shank is depressed by pressure on the key, the heel 56 will assume a position immediately to the rear of the firing bar, so that the firing bar will be stopped and held against rearward movement and thereby prevent the projections 35 on the hammer latch shanks from springing upwardly in advance of the firing bar, so that the hammers which would normally be fired on the return movement of the handle will be disabled. The key, when depressed, will be temporarily latched by engagement of the shoulder 55 with the end of the slot 54, so that continued pressure by the finger is not necessary during the operation of the handle.

If it is desired to hold the non-print key depressed during a succession of operations of the handle, this result may be effected by means of a lock lever 58 which is pivoted on the stud 52 and slotted to oscillate on the stud 51. The lock lever is provided with an inturned ear 59 which, when the non-print key is depressed, may be rocked forward into position to engage the upper end of the key shank, and thereby hold the same depressed independently of the latching engagement of the shoulder 55 with the end of the slot 54. The firing of the hammers can thus be dispensed with for as long a period of time as occasion may require.

In order to restore the hammers to normal position after firing, a restoring bar 60 is provided (see Fig. 2), which bar is carried by a pair of swinging arms 61, which arms are pivoted to a pair of studs 62, the formation being that of a universal bail which may be swung forwardly to engage and restore all of the hammers which may be fired. One of the arms 61 is provided with a rearward extension 62' carrying a roller 63 which rides upon a cam 64 mounted upon the main operating shaft 44, the arrangement being such that as the handle 130

is pulled forwardly, the restoring bar will be swung to the rear, thereby clearing all of the hammers and permitting the subsequent firing of those hammers which are subsequently unlatched by the action of the firing bar as previously described. During the completion of the return movement of the handle, the restoring bar will be swung forwardly to restore the hammers thus fired to latching position.

The cam actuated restoring arm 61 is also provided at a point adjacent the lower end of the key shank 48 with a cone-shaped stud 65 (see Fig. 2) which co-acts with a small non-print-restoring-latch 66 pivoted to the key shank 48 at a point immediately above the heel 56 thereof, a spring 67 being provided to hold the latch in its depressed position. The latch normally occupies a position above the cone-shaped stud on the restoring arm 61 which will thus ride under the latch when the non-print key is in elevated position. When, however, the key is depressed, it will cause the latch 66 to bear down upon the stud as in Fig. 4 at the time the non-print key is held down by the engagement of the shoulder 55 with the end of the slot 54. When the main operating shaft is rocked forwardly, the restoring arm 61 will be moved to the rear, thereby releasing the latch and allowing it to spring down into the line of return travel of the conical stud 65, so that on the return movement of the restoring bar and parts associated therewith, the stud will engage the rear end of the latch 66 and kick back the key shank 48 releasing the same and allowing the key to rise to normal position, save only in those cases where the key is locked in depressed position by a forward adjustment of the lock lever 58, in which latter case the kicking off of the shoulder 55 will, of course, have no effect in restoring the non-print key to normal position. When the non-print key is unlocked and depressed, it may be manually restored in case of an accidental or unintentional depression by pulling manually forward on the non-print key to effect a release of the shoulder 55 from the end of the slot 54.

Attention is now directed to the parts which hold the platen against its normal or usual rotation when the non-print key is depressed. Normally when the handle is operated, the lower end of the arm 68 which is mounted on a shaft 69 is free to rock forwardly by the action of a cam 69^a controlled by a link 69^b, and when the arm 68 is thus rocked to the limit of its forward movement, it effects the operation of the platen ratchet pawl 70^a to get a proper lead on the next tooth of the ratchet 70^b, shown in Figs. 6 and 7. Any usual form of platen ratchet operating mechanism may be employed, and these features, being well under-

stood in the art need no further description.

The arm 68 at its lower end is provided with a stud 70 which will ordinarily swing clear of a finger 71 on a block arm 72, which arm projects rearwardly from a mounting 73 freely journaled on a shaft 74. The mounting 73 carries the roller 75 which is adapted to be engaged by a toe 76 of the key shank 48 when the latter is depressed as in Figs. 4 and 5. With a depression of the shank, the block arm 72 will be swung upwardly into the path of movement of the stud 70, so that the normal movement of the latter will be blocked as in Fig. 5, thereby preventing sufficient amplitude of movement of the shaft 69 to effect an operation of the platen ratchet mechanism. When the non-print key is restored to normal position, the block arm 72 will be swung downwardly through the tension of a spring 77, thereby permitting the platen to be again operated in the normal manner. While, in many circumstances, it will be desirable to coordinate the non-print and spacing mechanisms in the manner described, it is plain that the key-controlled action of the non-spacing mechanisms may be omitted if a co-action of these features is not deemed desirable.

In operation, when the non-print key is depressed, it will be held down until restored by the return stroke of the handle. The depression of the non-print key will block the normal movement of the firing bar, so that normal unlatching of the hammers will be prevented, thereby permitting the adding and accumulating of the item introduced into the machine without effecting a printing thereof. The return movement of the handle will restore the hammers to latched position and simultaneously restore the non-print key to normal position unless the latter be locked down to prevent restoration during a succession of operations. The depression of the key likewise affects a disabling of the line spacing mechanism, so that the platen will not be rotated in the normal manner.

The various mechanisms herein described are so related to and harmonize with the adding machine mechanism that they interfere in no way with the normal operation of the adding machine, nor does the presence of the special mechanisms herein described require any substantial change or modification in the structure or arrangement of the parts for effecting the customary adding machine operation.

I claim:

1. In a mechanism of the class described, the combination of a main shaft, type carriers, hammers for the type carriers, latching means for the hammers, means controlled by the type carriers for normally effecting unlatching of the corresponding hammers, non-print mechanism for blocking

the normal operation of the latch releasing mechanism, means actuated by the main shaft for automatically restoring the non-print mechanism to normal position, locking 5 means for counteracting the effect of said restoring means, a platen, means for normally rotating the platen, and means actuated by the non-print mechanism for rendering ineffective the action of said platen 10 rotating means, substantially as described.

2. In a mechanism of the class described, the combination of type carriers, type carried by the carriers, hammers co-acting with 15 said type, a latch for each of said hammers co-acting with the corresponding type bar and adapted to be displaced by movement of the type bar, a firing bar with which the latch members are adapted to engage under the control of the type carriers and adapted 20 when moved to actuate the engaged number of latches to release the corresponding hammers, and non-print mechanism adapted when actuated to block the normal releasing movements of said firing bar, substantially 25 as described.

3. In a mechanism of the class described, the combination of type carriers, type carried by the carriers, hammers co-acting with 30 said type, a latch for each of said hammers co-acting with the corresponding type carrier and adapted to be displaced by movement of the type carrier, a firing bar with which the latch members are adapted to engage under the control of the type carriers 35 and adapted when moved to actuate the engaged number of latches to release the corresponding hammers, non-print mechanism adapted when actuated to block the normal releasing movements of said firing bar, and 40 means temporarily holding said non-print mechanism against return movement prior to the hammer firing stage in the operation, substantially as described.

4. In a mechanism of the class described, 45 the combination of type carriers, type carried by the carriers, hammers co-acting with said type, a latch for each of said hammers co-acting with the corresponding type carrier and adapted to be displaced by movement 50 of the type carrier, a firing bar with which the latch members are adapted to engage under the control of the type carriers and adapted when moved to actuate the engaged number of latches to release the corresponding hammers, non-print mechanism adapted when actuated to block the normal 55 releasing movements of said firing bar, means temporarily holding said non-print mechanism against return movement prior to the hammer firing stage in the operation, and means for ultimately restoring the non-print mechanism to normal position, substantially as described.

5. In a mechanism of the class described, 60 the combination of type carriers, type car-

ried by the carriers, hammers co-acting with said type, a latch for each of said hammers co-acting with the corresponding type carrier and adapted to be displaced by movement of the type carrier, a firing bar with which the latch members are adapted to engage under the control of the type carriers and adapted when moved to actuate the engaged number of latches to release the corresponding hammers, non-print mechanism adapted 70 when actuated to block the normal releasing movements of said firing bar, means temporarily holding said non-print mechanism against return movement prior to the hammer firing stage in the operation, means for ultimately restoring the non-print mechanism to normal position, and means for locking said non-print mechanism against the effect of said restoring mechanism, substantially 75 as described.

6. In a mechanism of the class described, the combination of type carriers, type carried by the carriers, hammers co-acting with 80 said type carriers, a latch for each of said hammers co-acting with the corresponding type carrier and adapted to be displaced by movement of the type carrier, a firing bar with which the latch members are adapted to engage under the control of the type carriers and adapted when moved to actuate the engaged number of latches to release the corresponding hammers, non-print mechanism adapted when actuated to block the normal 85 releasing movements of said firing bar, a platen, means for normally rotating the platen, and means actuated by the non-print mechanism for rendering ineffective the action of said platen rotating means, substantially 90 as described.

7. In a mechanism of the class described, the combination of type carriers, type carried by the carriers, hammers co-acting with 95 said type carriers, a latch for each of said hammers co-acting with the corresponding type carrier and adapted to be displaced by movement of the type carrier, a firing bar with which the latch members are adapted to engage under the control of the type carriers and adapted when moved to actuate the engaged number of latches to release the corresponding hammers, non-print mechanism adapted when actuated to block the normal 100 releasing movements of said firing bar, a platen, means for normally rotating the platen, and means actuated by the non-print mechanism for rendering ineffective the action of said platen rotating means, substantially 105 as described.

8. In a mechanism of the class described, the combination of type carriers, type carried by the carriers, hammers co-acting with 110 said type carriers, a latch for each of said

hammers co-acting with the corresponding type carrier and adapted to be displaced by movement of the type carrier, a firing bar with which the latch members are adapted 5 to engage under the control of the type carriers and adapted when moved to actuate the engaged number of latches to release the corresponding hammers, non-print mechanism adapted when actuated to block the 10 normal releasing movements of said firing bar, means for temporarily holding said non-print mechanism against return movement prior to the hammer firing stage in the operation, means for ultimately restoring 15 the non-print mechanism to normal position, a platen, means for normally rotating the platen, and means actuated by the non-print mechanism for rendering ineffective the action of said platen rotating means, substantially as described.

9. In a mechanism of the class described, the combination of type carriers, type carried by the carriers, hammers co-acting with said type carriers, a latch for each of said

hammers co-acting with the corresponding type carrier and adapted to be displaced by movement of the type carrier, a firing bar with which the latch members are adapted to engage under the control of the type carriers and adapted when moved to actuate the 25 engaged number of latches to release the corresponding hammers, non-print mechanism adapted when actuated to block the normal releasing movements of said firing bar, means for temporarily holding said non-print mechanism against return movement prior to the hammer firing stage in the operation, means for ultimately restoring the non-print mechanism to normal position, 30 means for locking said non-print mechanism against the effect of said restoring mechanism, a platen, means for normally rotating the platen, and means actuated by the non-print mechanism for rendering ineffective the action of said platen rotating means, 35 substantially as described.

HARRY LANDSIEDEL.
